UNITED STATES PATENT OFFICE.

JESSE M. HARR, OF WASHINGTON, DISTRICT OF COLUMBIA.

EGG-SHIPPING PACKAGE.

1,268,347.

Specification of Letters Patent. Patented June 4, 1918.

Application filed June 5, 1917. Serial No. 172,999.

To all whom it may concern:

Be it known that I, JESSE M. HARR, a citizen of the United States, and a resident of Washington, in the District of Columbia, 5 have made an Improvement in Egg-Shipping Packages, of which the following is a specification.

The object of my invention is to provide an improved package for use in shipping 10 eggs, the same being distinguished by a maximum safety as to its contents, and also by simplicity and economy of construction.

The details of construction, arrangement, and combination of parts embodying the invention are as hereinafter described, and 15 illustrated in the accompanying drawings, in which:

Figure 1 is a broken perspective showing a portion of an inclosing box or case with 20 my invention applied.

Fig. 2 is a perspective view of a portion of one of the cell case dividing or cushioning plates.

Fig. 3 is a vertical section of a portion of 25 a case.

Fig. 4 is a plan view of the same.

Fig. 5 is a detail vertical section of a portion of a double cell case.

My egg package comprises the following 30 parts or elements, to-wit: a cell structure for receiving eggs, and dividing and cushioning plates 2 and 3 (see Figs. 2 and 5). The said plates have circular openings for receiving the ends of the eggs, as shown in 35 Fig. 3, and around each opening there is a series of elastic fingers 4, projecting, respectively, up and down from adjacent plates 2 and 3, and bearing against and cushioning the extremities of the eggs α , as shown particularly in Fig. 3.

The cellular holder 3 is preferably formed of a series of paste-board strips or partitions, which are slotted transversely and intersect each other at right angles. The plates 40 2 and 3 are formed of thin elastic material, preferably pasteboard, and stamped to pro-

duce hollow ribs 6 and hollow conical protuberances 7 located at the intersection of the ribs. The latter stiffen the plates so that they may be produced from comparatively 50 thin and light material, and the grooves formed on their inner sides receive the edges of the cell partition 1, as shown in Figs. 3 and 5, and thus assist in supporting the partitions 1 against lateral pressure of the eggs 55 placed in the several cells.

The protuberances 7 strengthen and impart additional rigidity to the ribs at their several junctures, and also form so many cushions for the plates 2 and 3 as a whole. 60 As shown in Fig. 5, the protuberances 7 of adjacent plates 2 and 3 rest in contact and thus not only produce a double cushion effect, but hold the plates separated vertically by a space which prevents the opposed ends 65 of eggs α in adjacent tiers from coming in contact vertically, whereby maximum safety is assured.

I claim:

1. An improved dividing and cushioning 70 member for an egg case of the type indicated, the same consisting of an elastic plate having openings with surrounding elastic fingers, hollow ribs intersecting each other at right angles, and conical protuberances struck up 75 from the body of the plate and located at the intersections of said ribs and projecting above the plane of the ribs, as shown and described.

2. In an egg case of the type indicated 80 the combination with a series of superposed cell structures formed of partitions intersecting at right angles, of dividing and cushioning members consisting of an elastic plate having a series of registering openings with 85 surrounding elastic fingers, and intersecting hollow ribs extending around the openings and provided at their angles with struck-up protuberances that project from the plane of the ribs, as described.

JESSE M. HARR.
